UNITED STATES PATENT OFFICE.

ELLWOOD IVINS, OF PHILADELPHIA, PENNSYLVANIA, ASSIGNOR TO THE PATENT BUTTON COMPANY, OF WATERBURY, CONNECTICUT.

BUTTON-FASTENER.

SPECIFICATION forming part of Letters Patent No. 309,785, dated December 23, 1884.

Application filed April 28, 1884. (No model.)

To all whom it may concern:

Be it known that I, ELLWOOD IVINS, a citizen of the United States, and a resident of Philadelphia, Pennsylvania, have invented 5 certain Improvements in Combined Button and Fastener, of which the following is a specification.

My invention relates, mainly, to that class of button-fasteners in which a staple having 10 prongs adapted to pass through openings in the button is combined with a retainer, around which the ends of said prongs are clinched after passing through the button and the cloth to which it is to be attached.

15 The object of my invention is to prevent the prongs from being straightened out and pulled through the cloth by excessive strain upon the button, and this object I attain in the following manner, reference being had to 20 the accompanying drawings, in which—

Figure 1 is a perspective view of a button, staple, and retaining-ring constructed in accordance with my invention; Figs. 2 and 3, 25 sectional and Figs. 4 and 5 rear views showing the method of securing the button by the staple and ring, and Figs. 6 to 9 modified forms of retainer.

30 A is a button, having in the present instance four openings, *a*, for the passage of the prongs *b* of a staple, *B*, although more or less than this number of prongs and openings may be used, if desired. Each prong *b* has a straight shank terminating at the spear-point *e*, and has abrupt shoulders *ff*.

35 D is the retaining-ring, in the outer edge of which are as many recesses *d* as the staple has prongs, each recess being of a width slightly in excess of the width of the shank of the prong, but less than the width of the spear-point *e* of the same. When the staple is applied to the button and its prongs passed through the cloth *x*, said prongs are outside of the ring *D* and in line with the recesses *d* of the same, as in Figs. 2 and 4, so that when 45 the ends of the prongs are bent inward by the clinching device, as in Figs. 3 and 5, the shanks of the prongs enter the recesses, and any outward pull upon the prongs caused by strain upon the button will cause the shoulders *f* of 50 the spear-heads *e* to come in contact with the ring, and thus prevent the withdrawal of the prongs. A notched disk, Fig. 6, may be used in place of the ring *D*, if desired; but the ring

is preferred, as it permits the more effective clinching of the prongs; but when the ring is 55 used the inner edge of the same may be notched, as shown in Fig. 7, the prongs *b* in this case being clinched outwardly instead of inwardly.

Instead of a ring having a central opening 60 with which the notches communicate, the retainer may be made in the form of a disk with a series of openings, one for each notch, as in Fig. 8, these openings being large enough in diameter to permit the passage of the spear-heads of the prongs, and this construction being included in the term "edge notches."

65 My improvement can also be applied to that class of buttons in which the securing-prongs are struck up from the back of the 70 button, instead of forming part of a separate staple, an instance of such a button being shown in Fig. 9.

As regards the prior state of the art, it 75 should be stated that button-fastening prongs have been made with spear-like ends, but were not made with abrupt shoulders or used in connection with a retainer, as in my invention.

80 Button-fastening staples have also been made with two elastic pointed shanks, each having an abrupt shoulder, as in Patent No. 56,612; but in this case the hold of the staple on the removable button was due to the elasticity of the shanks, whereas in my invention the shanks are bent into notches in a retainer, the spear-heads overlapping the same, so as to form a permanent fastening.

I therefore claim as my invention—

85 The combination of the perforated button *A*, on one side of the fabric, the retainer *D*, arranged on the opposite side, and having the recesses *d*, with the staple *B*, having prongs, each of which consists of a shank terminating in a spear-head and having abrupt shoulders, 95 the shank of each prong being bent into a recess of the retainer, and the spear-head over the same, as set forth.

90 In testimony whereof I have signed my name to this specification in the presence of 100 two subscribing witnesses.

ELLWOOD IVINS.
